UNITED STATES PATENT OFFICE.

DAVID WILEY McCaughey, OF CHICAGO, ILLINOIS.

DIRIGIBLE TORPEDO.

SPECIFICATION forming part of Letters Patent No. 767,491, dated August 16, 1904.

Application filed March 20, 1902, Serial No. 99,116. (No model.)

To all whom it may concern:

Be it known that I, DAVID WILEY McCaughey, a citizen of the United States, residing at Chicago, in the county of Cook and State of Illinois, have invented certain new and useful Improvements in Dirigible Torpedoes, of which the following is a specification.

This invention relates to that class of torpedoes which is provided with self-contained mechanism by which the movements thereof may be controlled, and particularly to that class of torpedoes which is arranged to be controlled—that is, moved in any desired direction—by electrically-actuated mechanisms, all of which will more fully hereinafter appear.

The principal object of the invention is to provide a simple, economical, and efficient electrically-controlled torpedo.

A further object of the invention is to provide a torpedo with electrically-actuated mechanisms connected with the shore-line with a single insulated wire and arranged and constructed in such a manner as to be operated, directed, and controlled from the shore by means of the electric current passing through said wire.

The invention consists, further and finally, in the features, combinations, and details of construction hereinafter described and claimed.

In the accompanying drawings, Figure 1 is a diagrammatic view showing my improved controlling devices as they appear when used in connection with a torpedo. Fig. 2 is a plan sectional view of one form of torpedo as it appears when constructed in accordance with these improvements. Fig. 3 is a side elevation, partly in section, of the same; and Fig. 4 is an enlarged sectional detail of the upper part of spool-holding rod shown in the lower part of Fig. 3, as will be more fully hereinafter explained. Fig. 5 is a diagrammatic illustration of a reversible motor such as is used to turn the rudder.

In the art to which this invention relates it is well known that it is highly desirable to provide a means by which an explosive torpedo may be launched from the shore or from a vessel and directed toward a given mark and exploded by contact therewith or at any de-

sired point adjacent thereto. To accomplish this result, various devices and expedients have been used, some of which give more or less satisfaction and all of which contain objections which render their use somewhat undesirable. This invention, therefore, is designed principally to overcome as many objections of the prior art as possible and provide a simple, economical, and efficient torpedo which may be controlled from the shore by the use of a single conducting-line, which conveys currents of various intensities to the mechanism and is arranged to operate the desired mechanism, and thereby direct and control the movements of the torpedo, as will be hereinafter more fully explained.

In Fig. 1, A is a dynamo generating a constant current.

B is a dynamo generating an alternating current.

C is an electric motor whose armature is connected, by means of worms and worm-wheels, with the rudder-post of the torpedo in such a manner as to turn the rudder either to the right or left, as may be desired, in manner hereinafter described.

D is an electric motor whose armature is connected with the propeller-shaft.

E is a switch for changing the direction of the current.

F is a switch for cutting into circuit the constant or alternating current, as the operator may desire.

The motor C is constructed in such a manner that its armature will turn in a certain direction with a direct current and in the opposite direction with an inverse current.

The motor D is constructed in such a manner that its armature revolves in the same direction no matter whether a continuous or alternating current is used, and, is, furthermore, constructed in such a manner that it can be operated with either an alternating or continuous current, whereas the motor C can only be operated with the continuous current, but while an alternating current is passing through it its armature cannot rotate.

We will now suppose the mechanism to be in position represented in Fig. 1. The current will flow as follows: from dynamo A

through wire 1, arm 2, button 3, wire 4, wire 5, arm 6, button 7, wire 8, motor C, wire 9, motor D, wire 10 to the water at 11, thence through the water and land to 12, thence to wire 13, button 14, arm 15, and wire 16 back to the dynamo A. I choose to call this current the "direct" current. A continuous current being generated by A, both of the motors C and D will be operated. D will propel the torpedo forward. The armature-shaft of C is connected directly with the worm-shaft 17, (see Figs. 2 and 3,) which operates the worm-wheel 18, (see Fig. 2,) and thereby operates the screw 19, which is fastened upon the same shaft as 18. The screw 19 works in the worm-wheel 20, and 20 is affixed to the rudder-post 21. It is therefore apparent that by operation of the motor C the rudder 22, Fig. 3, will be turned to correspond with the motion of the worm-wheel 20. Now suppose the direct current will act upon the motor C in such a manner as to cause the rudder to turn from right to left. Then an inverse current will cause the armature of C to rotate in the opposite direction—that is, in such a manner as to turn the rudder from left to right. To reverse the motion of the armature of C, the operator turns the reversing-switch E so that arm 15 comes in contact with button 23. The current will then flow from dynamo A through wire 1, arm 2, button 14, wire 13 to the ground at 12, thence through the land and water to 11, then through wire 10, motor D, wire 9, motor C, wire 8, button 7, arm 6, wire 5 to button 23, thence through arm 15 and wire 16 back to the dynamo A, and the armature of C will now rotate in the opposite direction from that first above described, thereby turning the rudder 22 in the opposite direction from that first above described. D, however, is constructed in such a manner that the direction of rotation of its armature is not altered by reversing the current. The torpedo will therefore still be propelled forward, as before.

Now suppose it is desirable to propel the boat forward without moving the rudder in either direction. The operator therefore cuts out of circuit the continuous current and cuts into circuit the alternating current. This is done by moving the cut-out switch F so that arm 25 comes in contact with button 7. An alternating current will then flow from dynamo B through wire 26, arm 25, button 7, wire 8, motor C, wire 9, motor D, wire 10 to the water at 11, thence through the water and land to 27, thence through wire 28 back to the dynamo B. Inasmuch as the motor C is constructed in such a manner that its armature cannot rotate with an alternating current, the current last above described will pass through the motor C without affecting the position of rudder 22, while the torpedo will still be propelled forward, inasmuch as the

motor D is constructed in such a manner as 65 to be operated either with an alternating current or continuous current.

To provide means for holding the electric conducting-wire, which may be taken as wire 8 of the drawings, I prefer to put the spool G, 70 containing the same, in the torpedo, as shown in Fig. 3. Near the end of the wire, as at 29, Fig. 4, said spool is connected, by means of a button 30, with the brush 31, and thence the current is conducted to the motors, so that as 75 the torpedo is moved out there will be little or no drag of wire. The spool G is worked either upon a pointed pivot or ball-bearings, so as to cause as little friction as possible, and should be inclosed in a funnel-like apartment 80 40, Figs. 2 and 3, with an opening at 32 sufficient to allow the wire 8 to pass, which opening should be well back toward the stern of the torpedo in order to facilitate the unwinding of the spool G. It should be understood, 85 however, that the spool may be placed on the land and the wire be paid out automatically as the torpedo is directed or controlled.

Reversible motors are well known and in common use. In Fig. 5, however, I have 90 illustrated diagrammatically a reversible-motor mechanism, including a switch 130 such as I employ and which may be said to constitute a portion of such motor mechanism.

I will now describe the manner of reversing 95 the motion of the armature of the motor C. (See Fig. 1.)

In Fig. 5, C is a diagrammatic illustration of motor C as described in connection with Fig. 1 and which is used to turn the rudder in the 100 desired direction, as hereinbefore described.

In Fig. 5, 100 is a soft-iron wire-wound magnet, and 101 is a permanently-magnetized portion of a pivoted armature-bar 102, energized and placed adjacent to such magnet in 105 such a manner that the pole nearest the magnet will be attracted thereby whenever the magnet is energized by a direct current.

When the parts are in the position shown in Fig. 5, with electric current flowing from dynamo A (see Fig. 1) through wire 8 (see Fig. 1) around magnet 100, energizing it, armature 101 will be attracted and drawn down into contact with magnet 100, as shown in Fig. 5. The current will then flow from magnet 100 110 through wire 104, thence through pivoted armature-bar 102 to contact-post 105 and through the same, thence through contact-spring 106, thence through wire 107 and around field-magnet 108, energizing it, thence 115 through wire 109 and around field-magnet 110, energizing same, thence through wire 111, contact-spring 112, post 113, post 114, spring 115, wire 116 to and around armature-magnets 117, energizing same, thence through 120 wire 9 to motor D, and thence through wire 10 back to dynamo A, (see Fig. 1,) as hereinbefore described.

The armature and field magnets of motor C are wound in such a manner as to cause armature 117 to revolve in a given direction—that is, in such a direction as to cause the rudder to turn from right to left—when said motor C is operated by a direct current. Now if it is desired to turn said rudder from left to right the operator turns the reversing-switch E (see Fig. 1) so that arm 15 comes into contact with button 23, Fig. 1. The current will now flow through wire 8 in an opposite direction to that last described, and hence will flow around magnet 100 in such a direction as to cause it to repel armature-bar 101 until armature-bar 102 impinges against pin 127, in which position posts 118, 123, and 124 will be in contact with springs 119, 122, and 125, respectively, and contact between posts 105, 113, and 114 and springs 106, 112, and 115, respectively, will be broken. The current will now flow from dynamo A, through wire 9, Figs. 1 and 5, thence around armature-magnets 117, energizing same, thence through wire 116, wire 126, spring 125, metallically-connected posts 124 and 123, spring 122, wire 121, wire 107, thence around field-magnet 108, energizing same, thence through wire 109, thence around magnet 110, energizing same, thence through wire 111 and 120 to spring 119, thence through post 118, bar 122, wire 104, magnet 100, energizing same, as hereinbefore described, thence through wire 8 and back to the dynamo A in manner hereinbefore described.

It will be seen that the inverse current passes around the armatures 117 in an opposite direction to the direct current, the result being that the respective poles of the armature-magnets 117 will be reversed with reversal of current. It is also apparent that the direct current and inverse currents will flow around field-magnets 108 and 110 in the same direction and that therefore the polarity of the field-magnets will remain the same no matter whether a direct or inverse current be used, the result being that the direction of the motion of the armatures 117 will be reversed when the direction of the actuation-current is reversed, as hereinbefore suggested. Posts 105 and 118, Fig. 5, are so adjusted with reference to springs 106 and 119, respectively, that while magnet 101 is moving between magnet 100 and pin 127, as hereinbefore described, there is an instant of time when each of said posts is in contact with its respective spring, and in like manner there is an instant of time when posts 113 and 114 are in contact with springs 112 and 115, respectively, and posts 123 and 124 will respectively also be in contact with springs 122 and 125. These periods of double contact, however, last but for an instant, for when movable armature-bar 102 comes to rest, either by impinging upon pin 127 or by magnet 101 impinging against magnet 100, there will be a contact between the

respective posts and springs on one side only 65 of movable bar 102. Posts 113 and 114 and posts 123 and 124 are respectively insulated from bar 102.

In Fig. 5 I have illustrated a reversible motor C, (shown in Fig. 1,) including the switch 70 mechanism by means of which the direction of rotation of such motor is reversed and which switch mechanism may therefore be said to be an essential part of an ordinary reversible-motor mechanism. It will be understood, of course, that this or any ordinary and well-known form of reversible motor and switch mechanism may be employed.

When an alternating current is used, the armature of C will not rotate, because before 80 the direct current has time to overcome the inertia of the armature 117 and start it rotating in one direction an inverse current will act upon it and tend with exactly equal force to cause it to rotate in an opposite direction, 85 and these opposing forces will be brought into action in such rapid succession that the armature will remain balanced and stationary in whatever position it happens to be in when the alternating current is switched into circuit—that is, when dynamo B, Fig. 1, is in operation. Motor D, however, will operate with either a constant or alternating current, because it is wound in the ordinary manner, so that the currents flowing around its field 95 and armature magnets will always be correspondingly and simultaneously altered and reversed, no switch mechanism, such as 130, being used in connection therewith, the resultant effect being the same as though the actuating-current had not been reversed. Motor D is not a peculiar type, but the ordinary type of electric motors.

I claim—

1. In a torpedo of the class described, the 105 combination of propelling mechanism, rudder mechanism, an electric motor connected with the propelling mechanism and arranged to be operated by either continuous or alternating currents, an electric motor connected with the 110 rudder mechanism, a single line-wire connecting such motors with the shore, a continuous-current generator, an alternating-current generator, and a switch for cutting either of such motors into or out of the single-line circuit, substantially as described.

2. In a torpedo of the class described, the 115 combination of propelling mechanism, rudder mechanism, an electric motor connected with the propelling mechanism constructed to operate in one direction only and by either a continuous or an alternating current, a second motor connected with the rudder mechanism and constructed to be operated by a continuous current only, a single line-wire 120 connecting both of such motors with the shore, a continuous-current generator, an alternating-current generator, and a switch for cutting

either of such motors into or out of circuit with the single line-wire, substantially as described.

3. In a torpedo of the class described, the combination of propelling mechanism, rudder mechanism, an electric motor connected with the propelling mechanism and constructed to run in one direction only and by either a continuous or an alternating current, a second motor connected with the rudder mechanism constructed to be rotated by a continuous current only and be reversed as the direction of such current is reversed, a single line-wire for

electrically connecting both of such motors with the shore, a continuous-current generator, an alternating-current generator, switch mechanism for cutting either of such motors into or out of the single-line circuit, and a reversing-switch connecting the continuous-current generator with the single-line circuit for reversing the connection between such line and circuit, substantially as described. 15
